UNITED STATES PATENT OFFICE.

HARRY C. CAMPBELL, OF PITTSBURG, PENNSYLVANIA.

REGENERATIVE GAS-BURNER.

SPECIFICATION forming part of Letters Patent No. 337,130, dated March 2, 1886.

Application filed June 28, 1884. Serial No. 136,925. (No model.)

To all whom it may concern:

Be it known that I, HARRY C. CAMPBELL, of Pittsburg, in the county of Allegheny and State of Pennsylvania, have invented a new and useful Improvement in Regenerative Gas-Lamps; and I do hereby declare the following to be a full, clear, and exact description thereof.

My invention relates to an improvement in regenerative lamps; and it consists in the combination of a regenerative gas-lamp and a vapor-producer, so arranged that hydrocarbon vapors produced from petroleum or other oils or spirits may be employed in the lamp, either alone or with other gases, as hereinafter more fully appears.

I will now describe my invention, so that others skilled in the art may employ the same, reference being had to the accompanying drawings, forming part of this specification, in which—

Figure 1 is a vertical sectional view of a Siemens regenerative gas-lamp having the vapor-producer attached. Fig. 2 is a horizontal sectional view of the vapor-producer on the line *y y*, Fig. 3; and Fig. 3 is a vertical view of the same on the line *x x*, Fig. 2.

Like letters of reference indicate like parts wherever they occur.

In the drawings, *a* represents the inlet air-flue of the lamp, *b* the inlet gas-flue, and *c c'* the outlet and regenerative flue through which the products of combustion pass. These parts may be constructed in the ordinary manner and of the same materials as are now employed when the lamp is used in connection with coal-gas.

Around the lower portion of the lamp and attached thereto is a flaring cup, *f*, the purpose of which is to prevent the products of combustion passing off from the vapor produced from entering the lamp through the air-inlet flue *a*. The gas or vapor inlet pipe *b* of the lamp extends through and below the cup or deflector *f*. Secured to the end of this vapor-inlet pipe *b* is the supply-chamber *g* of the vapor-producer, the two pipes being united by a screw-thread or other suitable joint. This vapor-producer is formed of suitable cast metal having an inlet or oil-supply pipe, *h*, which enters near the top of the casting and passes thence by two horizontal branch passages, *i i*, around the vertical chamber *g*, where

the two passages *i i* unite. Extending vertically downward from the points where the passages *i i* branch from each other are the 55 passages *kk*, which communicate with the horizontal passage *m*, situate below the bottom of the vapor-chamber *g*, and which extends beyond the body of the vapor-producer inside of the annular flange *n*. Extending from the 60 bottom of the producer through the end portions of the passage *m* in the flange *n* are two screw-needles, *o o*, the points of which extend through small apertures *p p*, extending from the passage *m* through the upper portion of 65 the flange *n*, inclining at an angle toward the body of the producer. A similar and larger screw-needle, *q*, extends from the bottom of the producer vertically upward to the chamber *g*, intersecting the passage *m*, the needle-point 70 entering the vapor-chamber *g* through an aperture, *r r'*, similar to the apertures *p p*. Extending upward around the producer from the annular flange *r* at the top of the producer is a shield, *s*, inclosing that portion of the producer 75 between the flanges, and having air-inlet openings *s' s'* and exit-openings *s' s'*, for the products of combustion.

The screw-needles *o o* are provided with suitable handles, by means of which the apertures *p p r r'* may be opened or closed, so as to permit a regulated amount of oil or vapor to pass upward on the upper side of the flange *n*, and the vapor to pass from the passage *m* into the chamber *g*.

The supply-pipe *h* is connected with a suitable reservoir of light hydrocarbon oil or other suitable liquid hydrocarbon, whether oil or spirits.

The operation is as follows: The screw-needles *o o* being lowered in the apertures *p p*, the oil passes from the passage *m* to the flange *n*, where it is ignited, and the flame thereby produced striking against the sides of the body of the producer heats the same and converts the oil in the passages *i i* and *m* into vapor, a portion of which passes through the apertures *p p* and continues to support the flame above the flange *n*. As soon as vapor is produced in the passages *i i* and *m*, the screw-needle *q* is 90 lowered and the vapor passes from the passage *m* into the chamber *g*, into the inlet-flue *a* of the lamp, and thence through the burner-jets *a'*, at the mouth of which the vapor or gas 100

unites with the air which enters through the flue *b*, and, being ignited, the flame produced ascends around the porcelain cylinder *c*, and thence passes into the regenerative flue or 5 heating-chamber *c* with the products of combustion, which are drawn thence through the chimney *c*. The flame and products of combustion passing into the chamber *c* heat the walls of the same, and this heat is imparted 10 to the currents of air and vapor as they pass through the flues *a* *b*, converting the vapor into dry or superheated hydrocarbon gas before it reaches the mouth of the burner. Outside of the body of the lamp is a jacket of sheet 15 metal, *t*, between which and the body of the lamp a current of air ascends, which prevents the overheating of the lamp, and also increases the supply of air. On top of this outer casing rests a cylinder of glass, which protects the 20 flame from the action of the wind. At the base of the inlet-flue *b* is a branch pipe, *w*, which communicates with the flue *a*, and by means of which non-carbonized hydrogen or water gas or carbureted-hydrogen gas which 25 is deficient in carbon may be employed in the lamp in connection with the hydrocarbon vapor produced in the manner described.

The advantages of my invention are, that the regenerative lamps can be used with or 30 independently of a supply of coal-gas, and that the light produced from the combustion of the hydrocarbon vapor is greatly intensified by the action of the regenerative lamp, and the unpleasant and injurious products of combustion of hydrocarbon oil are removed by the 35 action of the heat, which converts the vapor into gas.

It is common in vapor-burners to employ a mixing-chamber wherein the vapor is combined with air before being introduced into 40 the burner. This chamber is omitted, however, by me in the vapor-producer used in connection with the regenerative lamp, as it is preferable that the vapor be used in its pure 45 state unmixed with air.

By means of the devices herein described the temperature of the vapor as it passes

through the lamp is brought to a sufficient degree of heat (about 900° Fahrenheit) to thoroughly disintegrate the vapor-globules and 50 form a fixed gas, which will not condense into a vapor or liquid when brought to its normal temperature, as I have proved by actual experiment.

Having thus described my invention, what 55 I claim, and desire to secure by Letters Patent, is—

1. The combination, in a regenerative lamp, of a gas-adit flue, and exit-flue for the discharge of the waste products of combustion, arranged 60 in proximity to the gas-adit flue, for the purpose of heating the same, and a vapor-producer communicating with the gas-adit flue, for the purpose of vaporizing hydrocarbon liquid and discharging its vapor thereinto, so that the 65 heat applied to said gas-flue by the exit-flue may be of sufficient temperature to convert said vapor into a fixed gas, substantially as described.

2. The combination of a regenerative lamp 70 and a vapor-producer arranged so that the hydrocarbon vapor shall pass directly from the producer into the superheating-flue of the lamp, substantially as and for the purposes specified.

3. A regenerative lamp having a vapor-producer connected therewith, in combination with a shield situate between the vapor-producer and the inlet-opening of the air-flue of the lamp, substantially as and for the purposes 80 specified.

4. In a lamp or illuminator, the combination of a hydrocarbon-vapor producer or generator, a heating-chamber for superheating the vapor before it passes to the burner, and a 85 burner, substantially as and for the purpose specified.

In testimony whereof I have hereunto set my hand this 24th day of June, A. D. 1884.

HARRY C. CAMPBELL.
